PERIMETER FENCE FITTING BRACKET

Michael S. Keegan, La Habra Heights, Calif., assignor to
Master Fence Fittings, Inc., La Habra, Calif.

Filed May 11, 1972, Ser. No. 252,532

Term of patent 14 years

Int. Cl. D8—08

U.S. Cl. D8—234

FIG. 1 is a perspective view of a perimeter fence fitting bracket;

FIG. 2 is a front elevational view of said perimeter fence fitting bracket;

FIG. 3 is a rear elevational view of said perimeter fence fitting bracket;

FIG. 4 is a left side elevational view of said perimeter fence fitting bracket; and

FIG. 5 is a plan view of said fitting.

The broken lines are for illustrative purposes only.

I claim:

The ornamental design for a perimeter fence fitting bracket, as shown and described.
